UNITED STATES PATENT OFFICE.

CHRISTIAN W. MEINECKE, OF JERSEY CITY, NEW JERSEY.

DESIGN FOR A BABY-COMFORTER.

SPECIFICATION forming part of Design No. 33,212, dated September 18, 1900.

Application filed July 18, 1900. Serial No. 24,111. Term of patent 14 years.

To all whom it may concern:

Be it known that I, CHRISTIAN W. MEINECKE, a citizen of the United States, and a resident of Jersey City, in the county of Hudson and State of New Jersey, have invented and produced a new and original Design for a Baby-Comforter, of which the following is a specification.

The design relates to the articles known as "baby-comforters;" and the feature of the design consists in the nipple, the base of which is below a shield, and said base of the nipple below the shield has an annular rib formation at the upper end of a pad, the nipple apparently constituting a portion of the pad. The pad has flat front and rear faces and edges formed upon the lines of compound curves.

In the accompanying drawings, Figure 1 represents a perspective view of a baby-comforter embodying the features of my design,

and Fig. 2 is a transverse section through the pad.

The nipple A is shown with an enlargement a, just above the shield B, which is of disk shape, and a further enlargement or rib a' appears in the nipple just below the shield B. The pad C is shown with a rounded bottom, flat front and rear faces, and side edges defined by compound curves.

Having thus described my invention, I claim as new and desire to secure by Letters Patent—

The design for a baby-comforter herein shown and described.

In testimony whereof I have signed my name to this specification in the presence of two subscribing witnesses.

CHRISTIAN W. MEINECKE.
